UNITED STATES PATENT OFFICE.

PAUL J. TIMBERLAKE, OF JACKSON, MICHIGAN, ASSIGNOR TO J. B. TIMBERLAKE & SONS, INC., OF JACKSON, MICHIGAN, A CORPORATION OF MICHIGAN.

COLOR-SCREEN HOLDER FOR ELECTRIC LIGHTS.

Application filed February 1, 1926. Serial No. 85,301.

My invention relates to holders for colored light screens used in the illumination of show windows and other places, which holders are adapted to be applied to and cover 5 the open ends of reflectors used with incandescent electric lamps, particularly reflectors of parabolic shape such as are now in common vogue.

In the accompanying drawings—

10 Fig. 1 is a perspective view of a holder embodying my invention applied to the reflector of an electric lamp.

Fig. 2 is a vertical sectional view of the same.

15 Fig. 3 is a view illustrating the holder opened to permit the insertion or removal of a light screen, such as a sheet of flexible colored gelatine.

Fig. 4 is a plan view of the holder separate 20 from the lamp reflector.

On the 19th of May, 1925 there was issued to me United States Letters Patent #1, 538,528 for a holder for colored light screens adapted to be applied to and used in 25 connection with parabolic reflectors for electric lamps, and my present invention relates to holders of the type illustrated in that patent, having for its object to improve the same in several particulars.

30 Referring to the drawing A designates an electric lamp fixture, B a shade or reflector carried thereby, and C a color sheet which is to be held across the open end of the reflector and close to the edge thereof so that 35 the light rays from the lamp shall be required to pass through such sheet and be colored thereby. These color screens are usually formed of extremely thin sheets of flexible gelatine and are quite fragile. In 40 the use of the holder as described in my aforesaid patent difficulty has been experienced in quickly and easily inserting the sheet constituting the color screen into the holder, and frequently such sheet is torn 45 or broken, either in the process of insertion or of removal. By the present invention the acts of inserting and removing color sheets are much facilitated, and the danger of breaking or otherwise injuring the sheets is 50 reduced to a minimum.

The holder consists of two frames, 2 and 3, overlying each other and hinged together along one edge, as at 4. The frames are of a shape to suit the use to which they are put, 55 being preferably square for use with re-

flectors of the shape illustrated in the drawings, and of a size ample to cover the rim or edge of the reflector. One of the frames is provided with means such as illustrated in my aforesaid patent for securing the holder 60 to the reflector. These means consist of a pair of fingers, 5 which extend diagonally part way across the frame, preferably from locations in proximity to the hinges 4, and serve to constitute stops that engage with the 65 edge of the reflector to which the holder is applied. Along the opposite sides of the frame are wires, 7, 7, constituting runners on which is supported a coiled spring 10, the middle portion of which is adapted to be sprung 70 over the edge of the reflector, as represented in Fig. 1 of the drawing and fully described in my said patent. These means for securing the holder to the reflector permit the 75 ready application of the holder to, and its easy removal from, the reflector, as may be required, and permit a holder of a particular size to be used in connection with reflectors of quite a wide variety of sizes and shapes. The frames 2 and 3 are provided respectively, 80 with cross wires, 8 and 9, those of one frame extending between the marginal side members thereof, while those of the other frame extend between the marginal end members thereof, an arrangement that 85 causes the wires 8 and 9 to cross each other at substantially right angles and to be one set above and the other set below the color sheet C when the latter is placed in the holder and the frames 2 and 3 are closed together. The construction of the frames as 90 described, that is with all the cross wires of each running in one direction, provides a support for the color sheet that is in a single plane; and as the color sheets, which 95 the frames herein described are intended to hold, are very thin and fragile, this is a very desirable feature. That frame in which the cross wires extend between the sides of the marginal wire of the frame, the upper frame, 100 2, in the arrangement illustrated in the drawings, may have the member of the marginal frame at the end which is hinged to the opposite frame entirely omitted, as the cross wires will hold apart and sufficiently brace the side members. This arrangement leaves the rear ends of the sides of the marginal frame free to be formed into eyes 105 11 that encircle the rear ends of the other marginal frame, and thus constitute the 110

hinges 4. The arrangement described also leaves the front end member 2^a of the marginal frame free to be sprung for a purpose that will presently be stated.

5 The other frame, 3, has its cross wires 9 extending between and uniting the end members of its marginal frame. This frame is provided at its front edge, and preferably at its center, with a projection 6, that is 10 adapted to have the resilient marginal member, 2^a, of the other frame sprung over it in order to lock the frames together and in closed relationship. This projection 6 is 15 conveniently formed by making the central cross wire 9 of the frame 3 a little longer than are the other wires and forming it into a loop or eye as illustrated, that serves as a catch to hold the two frames closed together.

In using the invention the two frame 20 members, 2, 3, are separated, as represented in Fig. 3, and a sheet C laid upon the cross wires of the lower frame. The frames are then closed, clamping the sheet between the wires 8 and 9, which cross each other, and the 25 edge member 2^a of the frame 2 is sprung over the projection 6 locking the frames together. The holder may now be used exactly as is the holder represented in my said 30 patent. The frames may be opened and closed while the holder is secured to the lamp reflector, as represented in Fig. 1, as well as when the holder is separate from the lamp.

What I claim is:

35 1. A holder for color sheets, consisting of a pair of frames hinged together and adapted when closed to hold between them the color sheet, the cross wires of one frame 40 extending between the marginal side members of the frame and being in a common plane, and the cross wires of the other frame 45 extending between the marginal ends of the second frame, and being in a common plane,

a catch for holding the frames closed together, and means for detachably securing 45 the holder to the reflector or shade of a lamp.

2. A holder for color sheets, consisting of a pair of frames hinged together, and adapted when closed to hold between them 50 the color sheet, one frame consisting of a marginal wire and cross wires between the sides thereof, and the second frame consisting of a marginal wire and cross wires between the ends thereof, one of the cross wires 55 of the second frame being formed into a catch and the end of the marginal wire of the first named frame that is opposite the hinge being resilient so as to be sprung into holding engagement with the catch carried 60 by the opposite frame.

3. A holder for color sheets, consisting of a pair of frames hinged together and adapted when closed to hold between them 65 a color sheet, one of the frames consisting of a marginal wire and intermediate cross wires extending between the ends of the marginal wire, and the second frame consisting of a marginal wire with two sides 70 and a single end, and cross wires extending between the sides of the marginal wire, the free ends of the sides of the said marginal wire being formed into eyes that surround the rear marginal end of the other frame, 75 thus constituting hinge connections between the frames, the front end of the marginal wire of the second frame being resilient, a catch carried by the front end of the marginal wire of the first frame with which the resilient front end of the second frame is 80 adapted to engage for holding the frames closed together, and means carried by the second mentioned frame for detachably securing the holder to the reflector or shade of a lamp.

PAUL J. TIMBERLAKE.
